[57] **CLAIM**

The ornamental design for a valve body, as shown and described.

DESCRIPTION

FIG. 1 is a perspective view, as seen from the top, front and left end of a valve body in accordance with the Applicants' design without a valve bonnet in place;

FIG. 2 is a perspective view, as seen from the top, rear and left end of the valve body of FIG. 1 with a valve bonnet in place;

FIG. 3 is a front elevation view of the valve body of FIG. 1; FIG. 4 is a left end elevation view of the valve body of FIG. 1;

FIG. 5 is a left end elevation view of the valve body of FIG. 2 (bonnet in place);

FIG. 6 is a rear elevation view of the valve body of FIG. 1; FIG. 7 is a bottom plan view of the valve body of FIG. 1; and,

FIG. 8 is a right end elevation view of the valve body of FIG. 1.
